UNITED STATES PATENT OFFICE.

WILLIAM EWALD MOLL, OF UNION CITY, NEW JERSEY.

SLICER.

Application filed July 2, 1928. Serial No. 289,806.

This invention relates to improvements in slicers, particularly to slicers for rolls in the preparation of Frankfurter sandwiches, and it is the principal object of my invention to 5 provide a slicer adapted to feed the rolls through the machine and subject the same to the slicing operation in approximately the center of the rolls in the direction of their longitudinal axis and allowing an adjustment of the feeding device as well as of the 10 depth of the cut according to the size of a roll.

Another object of my invention is the provision of a roll slicer of comparatively simple and inexpensive construction, yet durable 15 and efficient in its operation.

A further object of my invention is the provision of a slicer of this type equipped with a rotary turn-table having upper angularly 20 disposed radially upstanding ribs, and a lower depending flange provided with inner teeth adapted to be engaged by a gear of a train of gears allowing a regulation of the speed of operation by suitable selection of the 25 gears.

A still further object of my invention is the provision of a slicer of this character having adjustable gage plates and a slicer which can readily be attached to any support and re- 30 moved therefrom.

These and other objects and advantages of my invention will become more fully known, as the description thereof proceeds, and will then be specifically defined in the appended 35 claims.

In the accompanying drawings forming a material part of this disclosure:

Fig. 1 is a front elevation of a slicer constructed according to my invention.

40 Fig. 2 is a top plan view thereof with the cover partly broken away.

Fig. 3 is a side elevation thereof in section on line 3—3 of Figure 2.

Fig. 4 is a top plan view seen in the direction of arrows 4—4 of Figure 3.

As illustrated, the preferred form of construction includes a supporting bracket 10 having an upper substantially horizontally disposed arm 11, and near its lower end a 50 clamping face 12 against which a plate 13 at the upper end of a screw 14 operates passing through a perforated lower arm 15 of bracket 10, and equipped with a hand wheel 16, so that the slicer can be securely clamped to a 55 table or other support, the edge of which enters the recess formed in bracket 10.

This bracket has also formed intermediate its ends a bearing 18 for a shaft 19 projecting in front of said bearing and adapted to carry a hand wheel 20. The inner end of shaft 19 60 carries a bevel gear 20' in mesh with a bevel gear 20 angularly disposed thereto and arranged at the lower end of a vertical shaft 22 extending through bracket arm 11 and carrying thereupon a gear 23 in mesh with an intermediate gear 24 which in turn meshes with a gear 25, both gears being mounted on stub shafts journalled in arm 11. The gear 25 meshes with the inner toothed rim 26 of the depending flange of a plate 27 held by a bushing 28 on shaft 22, and revolving in a circular opening of a supporting plate 29. The upper face of plate 27 is provided with a plurality of radial, upstanding ribs 30 arranged at an inclination or angle towards the center of the 75 plate.

The bushing 28 carries a circular knife blade 31 revolving with shaft 22 and held in place by means of a nut 32 or the like.

The supporting plate 27 is provided in its 80 laterally extending arms with a plurality of pairwise arranged elongated slots 33, 34 allowing the passage from below of screws 35, 36 respectively which carry each at their lower ends thumb screws 37 and wing nuts 38 re- 85 spectively.

A front gage bar 39 having a median elongated slot 40 therein allowing the passage of the knife 31 having lower foot flanges 41 provided with recesses for the engagement 90 by screws 35. The rear gage bar 42 also has recessed foot flanges 43 formed therein for the reception of the screws 36, passing the slots 34.

At its upper end the rear gage bar 42 carries 95 a pair of eyes 44 for the reception of pins 45 of a cover plate 46 which in this manner is hingedly connected to rear gage plate 39. The front end of cover 46 when closed rests on a support 47 adapted to be equipped with 100 a suitable locking device.

A roller-shaped weight 48 having a corrugated periphery is rotatably mounted on a pin 49 projecting from the side of an arm 50 pivoted at one of its ends, as at 51, to the 105 rear face of rear gage 39 and normally held against the same in its lowermost position by means of a spring 52, the upper end of which is attached to a pin 53 on arm 50, while its lower end is attached to a pin 54.

110 The operation of my device will be entirely clear from the above description of the same

by simultaneous inspection of the drawing, and it will be understood that the device may be readily clamped to a table or other support by the proper operation of the hand wheel 16. The rolls are fed to the knife from the left hand side through a channel between the gages 39 and 42, while the pressure or weighted roller 48 will press the rolls against the upstanding radial flanges of circular plate 27 in the table 29. During the rapid rotation of shaft 19 by means of the hand wheel 20 the rolls will be fed from left to right, and the knife 31 will slice the rolls in the center of their longitudinal axis, and the rolls will be delivered at the right hand side of the machine.

On account of the adjustability of the gages the machine can be adjusted to guide any size of rolls through the same, while the weight can be adjusted to the proper height of the rolls.

The cover will protect the knife blade and the operator and if locked will prevent access to the interior mechanism by unauthorized persons. The rapidity of operation can be regulated by the proper selection of the gears constituting the train of gears.

It will further be understood that I have described and shown as an example of the many ways in which my slicer may be practically constructed, its preferred form only, and that I may make such changes in the general arrangement and in the construction of the minor details thereof as come within the scope of the appended claims without departure from the spirit of my invention and the principles involved.

Having thus described my invention, what I claim as new, and desire to secure by Letters Patent is:

1. In a slicer of the character described a bracket adapted to be clamped to a support, a table on said bracket having a median opening and a plurality of longitudinal slots, a vertical shaft, manually operated means for rotating said shaft, a train of gears rotated by said shaft, a circular plate in the median opening of said table, a depending flange on said plate, teeth on the inner periphery of said flange adapted to be engaged by the teeth of one of said gears of said train of gears to rotate said plate, a circular knife on said vertical shaft above said circular plate, a pair of vertical gages or guide plates, foot flanges therein, means passing through the elongated slots of said table, for adjustably securing said foot flanges to said table, a movable feed roller on one of said gages co-operating with said circular plate during the rotation thereof to feed the rolls engaged by said roller and said circular plate through the machine, and a cover hinged to one of said gages for covering the knife.

2. In a slicer of the class described, including a feed plate for rolls, means for rotating said feed plate, a pair of adjustable gages for guiding the rolls through the machine, a movable arm on one of said gages, a corrugated weighted roller, a pin on said arm carrying said roller, a spring controlling the movements of said roller, said roller pressing with its corrugated face against a roll and holding the same into engagement with said feed plate for feeding the rolls through the slicer during the operation of said feed plate.

Signed at New York, in the county of New York and State of New York this 27th day of June A. D. 1928.

W. EWALD MOLL.
